[57] CLAIM

The ornamental design for a speaker grill, as shown and described.

DESCRIPTION

FIG. 1 is a perspective view of a speaker grill, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a detailed view of the grill;

FIG. 9 is a perspective view of an alternative embodiment, the only difference being the shape of the grill;

FIG. 10 is a front view thereof, the rear view being a mirror image thereof;

FIG. 11 is a left side view thereof, the right side view being a mirror image thereof;

FIG. 12 is a top view thereof; and,

FIG. 13 is a detailed view of the grill.
